INVENTOR

Harrison Billings,

UNITED STATES PATENT OFFICE.

HARRISON BILLINGS, OF JAMESTOWN, NEW YORK.

LIFTING-JACK.

SPECIFICATION forming part of Letters Patent No. 449,515, dated March 31, 1891.

Application filed November 17, 1890. Serial No. 371,627. (No model.)

To all whom it may concern:

Be it known that I, HARRISON BILLINGS, a citizen of the United States, residing at Jamestown, in the county of Chautauqua and State of New York, have invented certain new and useful Improvements in Lifting-Jacks; and I do hereby declare the following to be a full, clear, and exact description of the invention, such as will enable others skilled in the art to which it appertains to make and use the same.

Figure 1 is a side elevation of my lifting-jack. Fig. 2 is a detail of the step K.

My invention relates to that class of lifting-jacks employing a lever and pawl-and-ratchet mechanism for raising and holding in an elevated position the article to be lifted; and my invention consists in the constructions and combinations of devices which I shall hereinafter fully describe and claim.

20 In the said drawings, A represents a base or support, to which is secured the vertically-disposed standard B, whose upper end is beveled or inclined at opposite sides to form seats a for the operating-lever C at the limit of its upward and downward strokes.

Bolted to opposite sides of the standard B and rising above the upper end thereof are plates D, between which passes the inner end of the operating-lever C, which is pivoted to 30 said plates by a bolt b, and is secured by a nut b' in the usual manner.

Above the lever C and passing through the plates D is a second bolt E, upon which is pivotally hung a pawl F, whose outer or free end is adapted for engagement with a rack-plate G, bolted to the upper surface of the lever C, and said lever has also secured to it a plate H, which projects beyond the inner end of the lever and is formed with an eye c.

40 In front of the standard B, and parallel with the same, is a vertical bar I, whose upper end is formed with a hook d, adapted to be engaged by the eye c on the plate H, whereby said bar is suspended directly from the lever.

45 To connect the lower end of the bar I with the standard, I employ links J, one on each side of the bar and standard, and having a pivotal connection at opposite ends to permit the free movement of the bar and to prevent 50 the same coming in contact with the standard.

The front face of the bar I is formed with

ratchet-teeth g, adapted to be engaged by a step K, which is designed to support the article to be raised. This step is made of a solid piece having a square hole in it of a size about 55 equal to the diameter of the bar I, which passes through it, and the front wall of the opening in said step engages the ratchet-face of the bar and serves as a pawl for retaining the step in position.

To give additional strength to the standard, I employ a brace L, which is bolted to the rear side of the standard and to the base-piece, as shown.

The operation of my device is substantially 65 similar to like devices now in use. When the vehicle or other article is to be lifted, the jack is placed alongside of it, the operating-lever elevated to cause a corresponding lowering of the ratchet-bar I, and the step adjusted 70 along the ratchet-face of the bar I until it fits under the desired part of the vehicle or article. The lever C is then pressed down, thereby elevating the ratchet-bar I and its step and lifting the vehicle or article the desired height, the pawl F in the meantime slipping over the rack-plate on the lever until the proper adjustment is obtained, when the pawl retains the jack in its position by 75 its engagement with the rack-plate. To lower the vehicle or article, the operator lifts the pawl F out of its engagement with the rack-plate, when the weight of the elevated structure causes the lowering of the ratchet-bar I and its load.

Having thus described my invention, what I claim as new, and desire to secure by Letters Patent, is—

1. In a lifting-jack, the base, the vertical standard, and the pivotally-secured operating-lever having a rack on its upper side, in combination with a vertically-disposed ratchet-bar suspended from the end of the lever, the links upon each side of the standard, pivotally secured thereto and also to the lower end 95 of the ratchet-bar, a step mounted upon the ratchet-bar, having a hole through which said bar passes, and a retaining-pawl for the operating-lever, substantially as herein described.

2. An improved lifting-jack consisting of a base, a vertical standard fixed thereto, the

plates D, bolted to the upper end of the standard and extending beyond its top, the operating-lever pivoted between said plates, having a rack-plate secured to its upper surface, 5 a plate H, also secured to said surface, projecting beyond the front of the lever and formed with an eye c, a pawl pivotally hung between the plates D and adapted to engage the rack-plate on the lever, a bar suspended by a hook from the end of the plate H, and having its front face formed with ratchet-teeth, two par-

allel links at the lower end of the bar pivotally secured thereto and to the standard, and a step on the ratchet-bar, having an opening through which the bar passes, substantially 15 as herein described.

In testimony whereof I affix my signature in presence of two witnesses.

HARRISON BILLINGS.
